UNITED STATES PATENT OFFICE.

GUSTAVE LAMBERT AND HENRI ALEXANDRE CARDOZO, OF PARIS, FRANCE, ASSIGNORS TO SOCIÉTÉ D'ÉTUDES POUR LA FABRICATION DES TUBES SANS SOUDURE, (BREVETS ET PROCÉDÉS LAMBERT-CARDOZO,) OF PARIS, FRANCE.

FEED MECHANISM FOR ROLLING-MILLS.

No. 923,189.

Specification of Letters Patent.

Patented June 1, 1909.

Application filed October 1, 1906. Serial No. 337,039.

To all whom it may concern:

Be it known that we, GUSTAVE LAMBERT and HENRI ALEXANDRE CARDOZO, citizens of France, residing, respectively, at 44 Rue du 5 Ranelagh and 54 Rue de Prony, in Paris, France, have invented new and useful Improvements in Feed Mechanisms for Rolling-Mills, of which the following is a specification.

10 The reduction of solid or hollow bodies in rolling-mills having a planetary motion is often effected at a high temperature in which case it is highly important to feed the work to the rollers as rapidly as possible in order 15 that the entire operation may take place at a substantially uniform temperature. In the case of hollow bodies, such as blanks for tubes, gun-barrels and the like, it is moreover desirable to impart to the metal a certain twist or torsion for the purpose of 20 destroying the longitudinal disposition of the fiber and of increasing the resistance of the tubular bodies to internal pressure.

25 The purpose of the present invention is to provide improved feed-mechanism by means of which the advantages indicated can be assured.

The invention is illustrated in the annexed drawing by means of an example.

30 Figures 1 and 1^a show a sectional elevation of the mechanism, Figs. 2 and 2^a show a plan view, and Fig. 3 a detail view.

The frame *a* of the improved feed-mechanism supports a hollow shaft *b* to which is 35 keyed a bevel wheel *c* meshing with another bevel wheel *d* fixed to a shaft *e*; the latter is adapted to be driven in either direction by means of a pulley *f* placed between two loose pulleys *f'*. The direction in which the shaft 40 *e* is driven depends on whether an uncrossed belt *g* or a crossed belt *g'* is placed upon the fixed pulley *f*. When both the said belts are on the loose pulleys, the mechanism is at rest. The shifting of the belt is effected by operating 45 a lever *y*. The mechanism by means of which the pulley *f* is driven is connected to the driving mechanism of the rolling mill *L* *L'* diagrammatically illustrated in Fig. 1 of the drawing; this mechanism is not illustrated in the drawing.

To the right hand end of the hollow shaft *b* (Fig. 1) is fixed an internally screw-threaded sleeve *h* in which works a screw spindle *i*.

The sleeve *h* revolves in a thrust-bearing *j* of great strength. To the sleeve *h* is keyed a 55 toothed wheel *k* which meshes with a toothed wheel *l* loosely mounted on a shaft *m*. The latter is of non-circular cross-section, and in order that the wheel *l* may revolve thereon a sleeve *n* of cylindrical circumference is interposed between the wheel and the shaft. 60

The left-hand face of the wheel *l* is provided with clutch-teeth adapted to coöperate with the teeth of a clutch member *o* slidable but not revoluble on the shaft *m*. 65

The screw-spindle *i* revolves in eyes formed in a guide or rider *p* mounted thereon and between the two eyes traversed by the spindle a toothed wheel *q* is keyed to the latter. This toothed wheel *q* engages a pinion *r* which 70 is slidable but not revoluble on the shaft *m*. To the right-hand end *s* of the spindle *i* is fixed a box *t* internally squared for the reception of the squared end of a rod *u*. The latter forms the mandrel on which tubular 75 blanks are fed to the rolling mill. For rolling solid bars or the like, a suitable dog-chuck is substituted for the rod *u*. The mandrel moves in suitable guides and the part *u'* thereof is of X-section in order to impart thereto a certain degree of elasticity in view of the torsional strains to which the mandrel is subjected. 80

The tubular blank *v* to be treated in the rolling mill is firmly secured to the mandrel 85 by being pressed through a draw-plate *x*.

The feed-mechanism described allows firstly, of advancing the work at high speed, and without rotation, for the purpose of moving it to a position near the point where the 90 action of the rolling mill begins. Secondly the feed mechanism allows of reducing, at the proper moment, the speed with which the work is advanced, and of imparting thereto a rotational movement which has the 95 double purpose of subjecting all parts of the tubular body to the action of the rollers, and of imparting at the same time, a powerful twist to the fibers of the metal. Thirdly the mechanism allows of returning the mandrel 100 at high speed to its original position when the rolling operation is completed. The manner in which these successive operations of the feed mechanism are produced is as follows: The uncrossed belt is placed on the fast pulley *f* and imparts to the sleeve *h* rotation by 105

which the screw spindle *i* is caused to move rapidly toward the right. When the work has passed through the draw-plate, the lever *y* is operated so that the uncrossed belt is 5 shifted to a loose pulley and the crossed belt is shifted to the fixed pulley *f*.

While the feed mechanism is momentarily at rest during the shifting of the belts a clutch-lever *z* (Figs. 2 and 3) is operated, so 10 that the toothed wheel *l* is coupled to the shaft *m* by means of the clutch-member *o* and is thus adapted to drive the pinion *r* and the toothed wheel *q* keyed to the spindle *i*.

The ratio of the toothed wheels and the 15 manner in which they are driven are such that although the screw-threaded sleeve *h* tends, after the reversal of the pulley *f*, to move the spindle *i* toward the left, the said spindle continues to move to the right owing 20 to the rotation imparted to the toothed wheel *q*. The speed at which the spindle moves at this stage of the operation is the resultant of the two differential motions imparted to it.

25 By altering the ratio of the two toothed wheels *k*, *l* and *q*, *r* the speeds at which the operations take place can be altered.

When the treatment of the work in the 30 rolling-mill has been completed, the clutch-member *o* is thrown out of gear, whereupon the screw-threaded sleeve *h* causes the spindle *i* to return at high speed to its original

position, no shifting of the belts being required for this purpose.

Having now described our invention, what 35 we claim as new and desire to secure by Letters Patent is:

A feed-mechanism for rolling-mills comprising in combination a sleeve provided with an internally screw-threaded portion, 40 means for imparting to said sleeve a rotary motion, a screw spindle engaging the screw-threaded portion of the sleeve, a toothed wheel secured to the sleeve, a toothed wheel keyed to the screw spindle, a shaft parallel to 45 the screw spindle, a toothed wheel revolvably mounted on said shaft and meshing with the toothed wheel secured to the sleeve, means for rendering the said revolvably mounted toothed wheel fixed in relation to said shaft, and a pinion longitudinally slidably secured on said shaft and meshing with the toothed wheel keyed on the screw spindle, substantially as described and for the purpose set forth.

50 In testimony whereof we have signed our names to this specification in the presence of two subscribing witnesses.

GUSTAVE LAMBERT.
HENRI ALEXANDRE CARDOZO.
